UNITED STATES PATENT OFFICE.

FRIEDRICH LUDWIG BARTELT, OF BRISTOL, ENGLAND.

APPARATUS FOR PREPARING BLEACHING LIQUOR.

No. 813,688.

Specification of Letters Patent.

Patented Feb. 27, 1906.

Application filed October 7, 1904. Serial No. 227,543.

To all whom it may concern:

Be it known that I, FRIEDRICH LUDWIG BARTELT, soap and chemical manufacturer, residing at 3 Kensington Place, Brislington, 5 Bristol, in the county of Somerset, England, have invented new and useful Improvements in Apparatus for Preparing Bleaching Liquor, of which the following is a specification.

In the accompanying drawings, Figure 1 10 is a front elevation of the apparatus. Fig. 2 is a plan view, and Fig. 3 is a sectional elevation of the same.

The object of this invention is to provide a 15 convenient well-arranged apparatus for preparing bleaching liquor to be used for various purposes in the arts—such, for instance, as in steam-laundries and places where only small quantities of bleaching liquor are required.

20 It is customary at this time to use bleaching liquor in steam-laundries for the purpose of bleaching the clothes or fabrics after they are washed, and it is essential that the bleaching liquor employed shall be of such a character that while it properly cleanses and bleaches it shall not act injuriously upon the fabrics. For the reason that no suitable and 25 convenient apparatus has been upon the market to prepare bleaching liquor as required by small users it has been usual to purchase bleaching liquor ready prepared in larger or smaller quantities and store it until required for use. The storing of bleaching liquor has obvious disadvantages consequent 30 upon the nature of the article, and it has been thought that if this liquor could be made on the premises in such quantities as may be necessary, say, for a single washing and without difficulty a great saving in many ways 35 could be effected.

40 A common and convenient way of producing bleaching liquor is by electrolysis, and as all large laundries as well as bleach-works nowadays use some motive power to drive the machinery that is employed in the business it has been thought that advantage 45 could be taken of this motive power to produce the electricity which is necessary for the electrolytic treatment of chemical solutions 50 in order to provide the bleaching liquor. In order, then, to carry out this object, an apparatus must be provided which will be complete in itself and which will occupy only a small floor-space. The parts should also be 55 convenient of access and the working should

be as far as possible automatic. To this end the apparatus should comprise a source of electricity, a solution-tank, an electrolyzer, and a product or liquor tank, to which may be added, so as to make the apparatus 60 complete in itself, a storage tank or box for the chemical and various details which will be more particularly defined hereinafter.

With a view to make the working automatic the solution-tank should be at a higher 65 level than the liquor-tank, the electrolyzer being placed in such a position with respect to the other two that the solution acting by gravity shall pass through the electrolyzer on its way to the product or liquor tank. This 70 arrangement will necessitate the use of a raised platform for the solution-tank, and upon the same platform I fix the source of electricity. I thus have a space below, which I can utilize as a place of storage for the 75 chemical.

Referring now to the drawings, A may be said to represent the platform, which, however, may be in one with the storage-chamber B. This chamber will be provided with 80 a door or doors conveniently placed for the insertion and withdrawal of the chemical.

C is a chamber, in which the source of electricity is placed, and, if necessary, it may also contain a speeding-up gear of any convenient 85 character. This source may be a small generator, which is driven by belts D from the shafting overhead. (Not shown.)

Where the electricity can be obtained from a public supply, I replace the generator by a 90 transformer or equivalent apparatus.

E is the solution-tank, which is provided (preferably in one corner) with an indicator F, by which the height of the solution in the tank may be seen and by which the filling of 95 the tank may be regulated. This indicator may take the form of a board with transverse divisions marked upon it to indicate so many gallons of water, according to the amount of the chemical put in. In other 100 words, the strength of the solution may be regulated by means of this indicator.

Near the bottom of the tank E two or more outlet-pipes G of various diameters are provided, each with a cock, and all these pipes 105 enter a common pipe H in connection with the top of the electrolyzer I. The object of providing two or more outlet-pipes of various sizes, each of which may be opened or closed independently of the other, is that the flow of 110

the electrolyte from the tank E to the electrolyzer may be accurately regulated, according to the strength of the liquor required by opening one outlet-pipe and closing another 5 or by opening both of the pipes. It is extremely difficult to regulate the flow from the tank E to the electrolyzer by a single outlet-pipe, as it is hard to turn the cock therein to a predetermined point to permit the proper 10 flow of the liquor from the tank E to the electrolyzer.

The electrolyzer I use may be of any convenient construction so long as the electrolyte is made to take a course while in the 15 electrolyzer during which it may remain a long time more or less in contact with the electrodes, and thus insure corresponding production of the bleaching liquor.

In the solution-tank, preferably in the corner behind the indicator-board, is provided 20 a float J of any convenient construction, adapted under certain circumstances to close one or more circuits. Thus it may close a bell-circuit K and an electrolyzing-circuit L.

25 When the level of the solution in the tank E descends below a certain point, the float J closes both these circuits, so that the bell is rung to call the attention of the attendant, and at the same time the switch is operated 30 to cut off the current to the electrolyzer, as otherwise the continuing current would produce a liquor of a character the use of which would be very detrimental to the well-being of the clothes into contact with which it 35 might be brought.

The labor employed in a laundry is not likely to be of a highly-technical character, and it is therefore necessary to employ means such as described to prevent accidents of the 40 kind indicated.

M is the bleaching-liquor tank.

The various tanks will be provided with 45 hinges or other covers, so that the parts may be kept clean and the escape of gases prevented as far as possible.

What I claim as my invention, and desire to secure by Letters Patent, is—

1. An apparatus for preparing bleaching liquor, consisting of a solution-tank, an electrolyzer, and a bleaching-liquor tank, arranged at different levels, in combination with a source of electricity in circuit with the electrolyzer, a bell-circuit and an electrolyzing-circuit, a measuring device in the solution-tank, a float in the solution-tank adapted to close the bell and electrolyzing-circuits and break the main circuit under certain conditions, and outlets of various diameters from the solution-tank to the electrolyzer, all substantially as described. 55

2. An apparatus for preparing bleaching liquor comprising a solution-tank, a float therein, an electrolyzer at a lower level than the tank, and a bleaching-liquor tank below the electrolyzer in combination with a source 60 of electricity in circuit with the electrolyzer, a bell-circuit and an electrolyzing-circuit including a switch adapted to be closed by the float, all substantially as described.

3. Apparatus for preparing bleaching liquor comprising a platform, a solution-tank on said platform and a source of electricity mounted on said platform, a storage-chamber situated under said platform, an electrolyzer below the level of the solution-tank, 70 and a bleaching-liquor tank below the electrolyzer, a main circuit between the source and the electrolyzer, a switch in this circuit, a float in the solution-tank, and an electrolyzing-circuit including a switch adapted to 75 be closed by the float, all substantially as described. 80

In testimony whereof I have signed my name to this specification in the presence of two subscribing witnesses.

FRIEDRICH LUDWIG BARTELT.
